UNITED STATES PATENT OFFICE.

JOHN T. LAMM AND FRED K. HUFFMAN, OF JULESBURG, COLORADO.

RADIATOR.

1,381,649.

Specification of Letters Patent. Patented June 14, 1921.

Application filed February 7, 1920. Serial No. 357,045.

To all whom it may concern:

Be it known that we, JOHN T. LAMM and FRED K. HUFFMAN, citizens of the United States, residing at Julesburg, in the county 5 of Sedgwick and State of Colorado, have invented certain new and useful Improvements in Radiators, of which the following is a specification, reference being had to the accompanying drawings.

10 This invention relates to certain improvements in radiators and has relation more particularly to a device of this general character especially designed and adapted for use in connection with the cooling system 15 of an internal combustion engine, and it is an object of the invention to provide a novel and improved radiator whereby the water is caused to travel therethrough in a tortuous or more particularly a zigzag course 20 or path of travel.

Another object of the invention is to provide a novel and improved radiator having disposed therethrough horizontally directed air tubes and wherein the interior of the radiator is divided vertically into a plurality 25 of compartments or chambers with adjacent chambers in communication one with the other, whereby the water within the radiator is caused to travel therethrough in a tortuous or zigzag course.

An additional object of the invention is to provide a novel and improved radiator wherein the walls or faces thereof are corrugated in order to increase the radiating 35 area and whereby the cooling of the water within the radiator is materially facilitated.

Furthermore, it is an object of the invention to provide a novel and improved device 40 of this general character wherein the air tubes are maintained in applied position in a manner whereby one of the tubes may be replaced independently of the remainder of the tubes and without the necessity of displacing the radiator from applied or working 45 position.

The invention consists in the details of construction and in the combination and arrangement of the several parts of our improved radiator whereby certain important 50 advantages are attained and the device rendered simpler, less expensive and otherwise more convenient and advantageous for use, as will be hereinafter more fully set forth.

The novel features of our invention will 55 hereinafter be definitely claimed.

In order that our invention may be the

better understood, we will now proceed to describe the same with reference to the accompanying drawings, wherein:

Figure 1 is a view partly in elevation and partly in section of a radiator constructed in accordance with an embodiment of our invention;

Fig. 2 is an enlarged fragmentary sectional view taken substantially on the line 65 2-2 of Fig. 1; and

Fig. 3 is a view in top plan of one of the plates as herein embodied.

As disclosed in the accompanying drawings, R denotes our improved radiator in its 70 entirety and which may be, if desired, suitably mounted within a radiator shell (not shown) although the structure of our improved radiator is such that the shell, under certain conditions, may be dispensed with. 75

Our improved radiator, as herein disclosed, comprises two sections, A and B, the upper section A constituting the upper tank of the radiator and the lower section B constituting the core. The walls of the sections 80 A and B are preferably made of sheet copper. When the sections are assembled, the adjacent marginal portions thereof are suitably connected or united as indicated by the seam 1. The upper or tank section A is also 85 provided with a conventional type of a filler neck 2 whereby the radiator and the coacting cooling system may be properly filled with water or other fluid.

The vertical walls of the section B of the 90 radiator R have produced therein the horizontally disposed and vertically spaced corrugations 3, said corrugations being preferably V-shape in cross section with their apices disposed inwardly of the section B. 95 It is also preferred that said corrugations 3 be equidistantly spaced. Between each pair of adjacent corrugations 3 is a flat surface 4 and disposed through said flat portions 4 of the front and rear walls of the section A 100 are the air tubes 5. Adjacent air tubes are in relatively close proximity and have their opposite end portions beaded to overlie the outer faces of the front and rear walls of the section B and said beads 6 are soldered 105 thereto. By this means, a single tube 5 can be readily removed and replaced independently of the remainder of the tubes and without the necessity of disassembling the radiator or removing the radiator from applied or working position. 110

Arranged within the radiator R is a plu-

rality of horizontally disposed plates 7, preferably of galvanized iron. Each of these plates rests upon diametrically opposed corrugations 3 in all of the walls of the section 5 B and one end portion of the plate 7 is provided with a relatively large recess or opening 8.

In the assembled structure, the plates 7 are preferably equidistantly spaced with the 10 recesses or openings 8 of adjacent plates at opposite sides of the radiator R so that the water or other fluid within the radiator will travel in a tortuous or zigzag path or course whereby the cooling thereof is materially 15 facilitated and especially by the air passing through the tubes 5. It is also to be understood that the corrugations 3 afford an increased area for the radiation of the heat whereby the cooling of the water or other 20 fluid within the radiator is materially facilitated.

We also find it of advantage to provide each of the plates 7 in the end portion thereof remote from the recess or opening 8 with 25 a restricted drain opening 9 whereby the requisite circulation of the water or other fluid is materially facilitated. The drain opening 9 is particularly advantageous when the radiator stands in an inclined position.

30 The pans 7 divide the interior of the radiator R or more particularly the section B thereof into a plurality of superimposed chambers or compartments and the lowermost of such compartments serves as the 35 bottom tank and has in communication therewith an outlet connection 10 of any ordinary or preferred type. The upper section A has in communication therewith an inlet connection 11. It is also to be understood 40 that our improved radiator may be employed with a thermo-siphon cooling system or any other system wherein water or other liquid is employed.

In practice, it is also to be understood 45 that our improved radiator is adapted for use in connection with passenger automobiles, trucks, tractors, gasoline engines, or any machine which embodies a liquid cooling system.

From the foregoing description, it is 50 thought to be obvious that a radiator constructed in accordance with our invention is particularly well adapted for use by reason of the convenience and facility with which it may be assembled and operated, and 55 it will also be obvious that our invention is susceptible of some change and modification without departing from the principles and spirit thereof, and for this reason, we do not wish to be understood as limiting ourselves to the precise arrangement and formation of the several parts herein shown in carrying out our invention in practice except as hereinafter claimed.

We claim:—

1. A radiator of the class described comprising a hollow casing having induction and eduction openings at the top and bottom thereof, and a plurality of vertically spaced plates arranged within the casing and dividing the same into superimposed compartments, an end portion of each of the plates being provided with an opening affording communication with the compartment immediately therebelow, the walls of the casing being provided with inwardly extending corrugations, certain of said corrugations serving as supports for the plates.

2. A radiator of the class described comprising a hollow casing having induction and eduction openings at the top and bottom thereof, a plurality of vertically spaced plates arranged within the casing and dividing the same into superimposed compartments, an end portion of each of the plates being provided with an opening affording communication with the compartment immediately therebelow, the walls of the casing being provided with inwardly extending corrugations, certain of said corrugations serving as supports for the plates, and air tubes extending through the casing at points between adjacent corrugations.

In testimony whereof we hereunto affix our signatures.

JOHN T. LAMM.
FRED K. HUFFMAN.
